UNITED STATES PATENT OFFICE.

LEWIS J. BAZZONI, OF SWAMPSOFT, MASSACHUSETTS, ASSIGNEE TO UNITED SHOE MACHINERY CORPORATION, OF PATERSON, NEW JERSEY, A CORPORATION OF NEW JERSEY.

BUTTONING-MACHINE.

1,400,714.

Specification of Letters Patent. Patented Dec. 20, 1921.

Application filed June 15, 1918. Serial No. 240,208.

To all whom it may concern:

Be it known that I, Lewis J. Bazzoni, a citizen of the United States, residing at Swampscott, in the county of Essex and 5 State of Massachusetts, have invented certain Improvements in Buttoning-Machines, of which the following description, in connection with the accompanying drawings, is a specification, like reference characters on 10 the drawings indicating like parts in the several figures.

This invention relates to buttoning machines and is herein shown as embodied in a machine particularly designed for performing buttoning operations upon boots, shoes, gaiters, and the like. More particularly the invention is herein illustrated as embodied in a construction conveniently useful for buttoning a comparatively small 20 number of the buttons on the upper of a button shoe prior to the operation of lasting the shoe in order that the button piece and the buttonhole fly shall be held in such relation as to insure the proper lasting of the 25 shoe. It should be understood, however, that the invention is not thus limited in its applicability to machines for buttoning uppers prior to lasting, nor to machines for buttoning work of this particular character.

An important feature of the invention resides in novel means for relatively manipulating a button and a buttonhole fly to perform a buttoning operation in such manner 35 that the button is caused to enter the buttonhole edgewise. In the illustrative construction herein shown the button is positioned in a fork which embraces its shank portion and the material about a buttonhole is moved 40 lengthwise of the fork to force it over the head of the button, the fork being so constructed as to permit it to enter the buttonhole as the material is forced over the button head. It should be understood, however, 45 that the invention in its broader aspects is not limited to movement of the buttonhole fly relatively to the button to perform the buttoning operation but contemplates broadly relative movement of the button 50 and the material about a buttonhole.

Another feature of the invention comprises means for guiding a button to its proper position in the machine and novel means for causing said guiding means sub-

sequently to be disposed in such relation to 55 the button as to present no obstruction to the performance of the buttoning operation. In the illustrative construction in which the button is positioned for the buttoning operation in a shank embracing fork, an auxiliary 60 fork is provided which, in the initial relation of the parts, forms substantially an extension of said positioning fork, and the auxiliary fork is moved lengthwise by the operation of the machine to withdraw it to an inoperative position.

A further feature of the invention resides in a novel construction and arrangement of buttonhole fly positioning means and mechanism for causing said means to be disposed 70 in such relation to the buttonhole fly as to leave the buttonhole free to be entered by the button. The construction herein illustrated as an embodiment of this feature comprises a member arranged to project laterally of the head of a button for engagement 75 in a buttonhole to position the buttonhole opposite to one side of the button head, and mechanism for moving said member to withdraw it from the buttonhole. In this illustrative construction the buttonhole positioning member is connected with the button guiding means above referred to, to cause 80 both this member and the guiding means to move together into and out of operative 85 position, but it should be understood that the invention in its broader aspects is not limited to this particular embodiment.

Still another feature of the invention comprises novel means for ejecting the work 90 from the machine, this function in the construction shown being performed by the button guiding means and the buttonhole fly positioning means during their return to operative position after the buttoning operation has been performed.

The machine herein shown includes also novel power transmission mechanism for imparting operative movement to the buttoning means, whereby an economy of space 100 and other advantages are secured, and such mechanism constitutes a further important feature of the invention.

The above and other features of the invention, including certain details of construction and combinations of parts, will now be described with reference to the accompanying drawings and pointed out in the claims.

In the drawings,

Figure 1 is a perspective view of a machine in which the invention is embodied, with a portion of the inclosing casing broken away to show the interior construction;

Fig. 2 is a vertical section in a plane extending centrally of the machine from front to back;

Fig. 3 shows in side elevation one of the several sets of instrumentalities with which the machine is provided for use in performing buttoning operations, portions of the associated structure of the machine being shown in vertical section;

Figs. 4 and 5 are views similar to Fig. 3 showing the parts as positioned at successive stages of the cycle of operations;

Fig. 6 is a perspective view of a portion of the mechanism shown in Fig. 3, illustrating the relative positions of the parts at that stage of the cycle of operations when the material about a buttonhole has been forced partly over the head of a button;

Fig. 7 is a view similar to Fig. 6 illustrating the relative positions of the parts at the same stage of the cycle of operations as in Fig. 5, the buttonhole fly engaging members being shown at the end of their operative movement, and

Figs. 8 and 9 are views in vertical section showing a portion of the operating mechanism of the machine at different stages of the cycle of operations subsequent to the beginning of the operative movement of the parts from the starting position indicated in Fig. 2.

The operative portions of the machine are supported upon a base casting 2 and, with the exception of a comparatively small portion of the mechanism at the front, are normally inclosed in a detachable casing 4 a fragment of which is shown in Fig. 1. Secured to the base 2 is a frame casting 6 upon which the various instrumentalities for performing the buttoning operations are mounted. The machine shown comprises a plurality of sets of co-operating instrumentalities for performing several buttoning operations simultaneously, each of the sets comprising means for receiving and positioning a button attached to a button piece, means for guiding the button to the button positioning means, a member constructed and located for engagement in a buttonhole to position the buttonhole relatively to the button, and means for engaging the buttonhole fly and forcing the material about a buttonhole over the head of the button. In the machine shown these sets are seven in number in order to adapt the machine for buttoning seven buttons at each presentation of a piece of work to the machine, but it will be understood that the number of the sets may be varied as desired. The central set, as a unit, is stationary with the frame

6, as shown in Fig. 2, and comprises a supporting frame 8 secured to the casting 6 by means of a screw 10 and a bolt 12. The other sets of instrumentalities are movable relatively to the central set and to each other to conform to differences in the spacing of the buttons and the buttonholes in different pieces of work, each of the movable sets comprising a frame member 14 which is forked at its rear end and provided with flanges 16 for engagement in transverse slots formed in the opposite ends of a pin 18 which is mounted for turning movement in a bearing formed in a bracket 20 secured to the frame casting 6. Each of the frames 14 is thus permitted to swing about the axis of its positioning pin 18 and also to move forwardly and backwardly by reason of the provision for sliding movement of the flanges 16 in the slots at the ends of the pin. Each of the frames 14 on its front end portion is provided with a bearing block 22 which is slidably supported upon a bearing plate 24 on the frame, the block 22 being provided with an upwardly extending lug 26 for engagement with the front edge of a bar 28 which overlies the several blocks 22 and prevents them from rising from the bearing 24, this bar by engagement with the lugs 26 also serving to limit backward movement of the frames 14. Forward movement of the frames 14 is limited by means of a bearing plate 30 which engages a portion of the mechanism carried by each of the movable frames. The bar 28 and the plate 30 are curved, as shown clearly in Fig. 1, to

approximate the curve of a row of buttonholes in a buttonhole fly, the several movable sets of buttoning instrumentalities thus being arranged in a series on a curve approximating the curve of a row of buttonholes to facilitate the presentation of the work to the machine, and confined to such curve in all positions of relative adjustment of the sets.

In order to insure that the several sets of instrumentalities shall be substantially equidistantly spaced in all positions of their relative adjustment, a controller plate 32 is pivoted centrally upon the screw 10 hereinbefore mentioned, and is provided with a plurality of slots 34 to receive rolls 36 carried by the frames 14, the rolls being somewhat loosely received in the slots in order to permit each of the frames to move laterally to a small extent independently of the others to conform to possible slight variations in the spacings of the buttons or buttonholes on the same piece of work. The slots 34 are so formed relatively to the arc of swinging movement of the plate 32 as to cause the plate to effect proportional movements of the frames 14 such as to maintain their front end portions in substantially equidistant relation and also to maintain sub-

stantially the same equidistant relation between the central set of instrumentalities and the sets adjacent to the opposite sides of the central set. It will be evident 5 that with this construction adjusting movement of the several sets of instrumentalities carried by the frames 14 may be readily effected by engaging and moving any one of these movable sets laterally, any necessary 10 small adjustment ordinarily being effected by pressure of the work when the work is presented to the machine in the manner hereinafter set forth.

Each of the movable frames 14, and also 15 the fixed central frame 8, is provided at its front end with lugs 38 which support a rod 40, this rod being mounted for lengthwise adjusting movement through the provision of adjusting nuts 42 at opposite sides of 20 the lower lug. The rod 40 on its upper end face is provided with a slightly hollowed recess for engagement with the laterally curved surface of the head of a button, and in front of said recess the rod is shaped to 25 provide a short upwardly projecting fork 44 which is constructed and arranged to embrace the shank of the button underneath the button head, this fork being sufficiently narrow to permit it to enter a buttonhole. 30 Slidably mounted on the rod 40 is a bracket 46 which is provided with a pair of spaced sleeves 48 mounted in bearing engagement with the rod 40 and connected by a strap 50 (Fig. 1). The bracket 46 carries an auxiliary fork 52 positioned in front of the fork 44 and arranged to extend upwardly beyond the end of the fork 44 when the parts are in work receiving position as shown in Figs. 1 and 3. The slot in the fork 52 is comparatively wide at its upper end and tapers downwardly to the width of the slot in the fork 44 of which it forms substantially a continuation, the several auxiliary forks thus serving 40 as guiding means to facilitate the presentation of the several buttons to the forks 44.

Carried also by each bracket 46 is an upwardly projecting finger 54 extending upwardly beyond the end of the guiding fork 52 in substantially parallel relation to the 50 rod 40, these fingers being constructed and arranged each to project through a buttonhole and to position each buttonhole relatively to its button with the lengthwise dimension of the buttonhole substantially perpendicular to the plane of the button head (i. e., a plane perpendicular to the shank of the button) and with the plane of the buttonholes approximately parallel with the plane of the shanks or of the axes of the 55 buttons when the work is presented to the machine. By reference to Fig. 3 it will be seen that the buttonhole fly *a* as thus positioned by the fingers 54 extends transversely across the ends of the auxiliary guiding 60 forks 52 and hangs downward in front of

the buttonpiece *b* to which the shanks of the several buttons in the forks 44 at the upper ends of the rods 40 are attached by the usual stitches or staples.

For performing the buttoning operations 70 each of the several sets of instrumentalities is provided with an operating member 56 pivotally mounted at 58 on the supporting frame, this member carrying an arm 60 the front end of which is formed to provide diverging fingers 62 curved in approximate conformity to the transverse curve of the head of a button over the top of the head and arranged to engage the buttonhole fly at the outer end of the buttonhole and at 80 the opposite side edges of the buttonhole adjacent to the lateral edges of the head of the button. In the machine shown one of the fingers 62 of each of the arms 60 is slightly shorter than the other finger, the 85 object of this construction being to prevent interference between the fingers of adjacent arms when the machine is adjusted for operating upon work on which the buttons and buttonholes are very closely spaced. Carried also by each alternate member 56, comprising in the construction shown four of the seven members, is a second arm 64 which is formed of spring metal and curves upwardly and then downwardly below the outer end of 90 the arm 60 for engagement with the buttonhole fly substantially opposite to the inner end of the buttonhole. It will be evident by reference to Figs. 4 to 7 inclusive that during the operation of the member 56 to swing 95 the arms 60 and 64 downwardly, the arm 60 with its fingers 62 forces the material at one end and at the opposite sides of the buttonhole down over the head of the button while the button is supported in the fork 44 with the lower side of the button head abutting against the upper end of the rod 40. During this movement of the arm 60 the spring arm 64 presses yieldingly against the buttonhole fly in sliding engagement with it and thus resists any tendency for undue displacement of the buttonhole fly lengthwise of the buttonhole by the action of the comparatively rigid arm 60, while also assisting in forcing the material over the head of the button. The members 64 of alternate sets 100 are omitted in order to avoid interference between these members when the machine is adjusted to operate on work on which the buttons are closely spaced, the four members provided being sufficient to prevent displacement of the work and in coöperation with the members 60 to insure the effective buttoning of the work. In the final location of the parts, as shown in Figs. 5 and 7, the material at the opposite sides of the buttonhole is carried well below the widest part of 105 the head of the button, the material being forced downwardly to such an extent that the button positioning fork 44 projects through the buttonhole. When the parts are 110

disposed in this relation the buttoning operation is effectively completed, the button automatically assuming an upright position relatively to the work when the pressure 5 upon the buttonhole fly is released.

During the operation of the buttonhole fly engaging means in the manner above explained, the guiding fork 52 and the finger 54 of each set of instrumentalities are with- 10 drawn from operative position to avoid interference with the action of the arms 60 and 64 upon the work. For this purpose there is pivotally mounted at 66 on each of the frames 14, and also on the frame 8, 15 a lever 68 having a pin and slot connection at its front end with the bracket 46. For operating the lever 68 the operating member 56 carries an arm 70 provided with a pin 72 for engagement in a slot in the lever. This 20 slot comprises a portion 74 which is substantially concentric to the axis of movement of the member 56 and another portion 76 extending at an angle to the portion 74. It will be evident that in the operation of 25 the parts as thus constructed the first portion of the movement of the member 56 will carry the arms 60 and 64 toward the work without imparting any movement to the lever 68 and the connected bracket 46. This 30 permits the buttonhole fly engaging members to be carried substantially or approxi- mately into engagement with the work before the withdrawing movement of the fork 52 and the finger 54 begins. During con- 35 tinued movement of the parts the pin 72 by its engagement with the lever 68 in the portion 76 of the slot operates the lever to impart downward movement to the bracket 46, the bearing lugs 48 sliding downward along 40 the rod 40. It will be evident that the finger 54 is not immediately withdrawn from the buttonhole since the buttonhole fly, which is initially positioned by the guiding fork 52 above the head of the button, is carried 45 downward bodily during the downward movement of the bracket 46 and the button- hole fly engaging members until it comes into engagement with the head of the button as shown in Fig. 4. During the continued 50 movement of the parts after the button hole fly encounters the resistance of the button, the finger 54 is withdrawn from the button- hole and thus presents no obstruction to the action of the arm 60, the guiding fork 52 55 likewise being further withdrawn to permit the buttonhole fly to be forced down over the end of the button positioning fork 44. A spring 78 connected to each of the mem- bers 56 serves to position the parts normally 60 as shown in Fig. 3 and to return them to starting position.

For imparting operative movement to the several members 56 to operate the various sets of instrumentalities in the manner above 65 explained, the machine is provided with a

bar 80 carried by an arm 82 of a bell crank lever which is mounted on a pivot rod 84, the other arm 86 of the bell crank extending rearwardly in the direction of an operating cam 88 mounted on a driving shaft 90 be- 70 yond the end of the arm 86. The bar 80 is arranged to engage rolls 92 on the rear ends of the members 56, these rolls being positioned initially in engagement with the rear- 75 wardly facing surface of the bar which is curved similarly to the members 28 and 30 to cause the rolls 92 to remain in the same operative relation to the operating bar in all positions of lateral adjustment of the several frames 14. Operative movement is 80 imparted to the members 56 by rearward movement of the bar 80, the rolls 92 finally riding upon the top surface of the bar, as shown in Fig. 5. Movement of the members 56 is thus limited irrespective of any further 85 rearward movement of the bar 80.

For causing the lever arm 86 to be operated by the action of the cam 88 a construc- 90 tion is provided whereby an economy of space in the operating mechanism is effected 95 and the desired movement of the arm is obtained by the use of a cam of comparatively short throw. To this end there is mounted on a pivot 94 on the outer end of the lever 86 a bracket 96 which serves as a link to sup- 100 port a bell crank lever comprising two arms 98 and 100, this member being mounted on a pivot 102 on the bracket. The arms 98 and 100 carry rolls 104 and 106 which are ar- 105 ranged to engage the periphery of the cam 100 88. A screw 110 adjustably mounted on the lever 86 and engaging a lug 112 on the bracket 96 serves to adjust the bracket about its pivot 94 to insure the correct relation of the rolls 104 and 106 to the cam 88, and also 110 by varying the angular relation between the lever 86 and the bracket 96 to determine the initial position of the lever 86 and of its connected arm 82 and bar 80. The cam 88, 115 which is mounted for rotation in the direc- 120 tion of the arrow (Fig. 2), is provided with a low concentric peripheral surface extend- 125 ing substantially from the point *c* to the point *d*, a rise extending from the point *d* to the point *e*, a higher concentric surface 130 extending from the point *e* to the point *f*, and a return declivity extending from the point *f* to the point *c*. In the starting posi- 135 tion of the parts indicated by Fig. 2 the rolls 104 and 106 are in engagement with the cam substantially at the points *d* and *c*. In the movement of the cam from the position shown in Fig. 2 to the position shown in Fig. 8 the cam operates upon the roll 104 to swing the lever 98, 100 about its pivot 102 while the other roll 106 is in engagement 140 with the low concentric surface of the cam which thus serves as an abutment upon which the lever fulcrums, the roll traveling slightly along the surface of the cam as the 145

arm 100 comes more nearly into parallel relation to the lever 86. It will be evident that during this movement the force is applied by the cam to the arm 98 in a direction approximately parallel to the lengthwise dimension of the lever 86, this force effecting through the lever 98, 100 and the bracket 96 a downward swinging movement of the lever 86. After the portion of the peripheral surface of the cam indicated at *e* has arrived in position to engage the roll 104, the cam ceases to impart movement to the arm 98. That portion of the periphery of the cam indicated at *d*, however, arrives substantially simultaneously in position to engage the roll 106, and as operative movement of the arm 98 ceases, the cam begins to operate upon the roll 106 to impart an operative movement to the arm 100. Since the roll 104 is now in engagement with the high concentric surface of the cam, the lever 98, 100 is substantially restrained from movement relatively to the lever 86 and the arm 100 acts virtually as a rigid extension 25 of the lever 86 through which power is applied to said lever to continue its movement until the portion of the cam indicated at *e* arrives in position to engage the roll 106. Both rolls 104 and 106 now ride upon the higher concentric surface of the cam, as shown in Fig. 9, without imparting any further movement to the lever 86. Through continued movement of the cam the parts are finally permitted to return to starting 35 position under the action of a spring 114 connected to the lever 86.

It will be evident that in the use of the mechanism above described a substantially continuous movement is imparted to the lever 86 by the action of the same portion of the cam 88 successively upon the crank arms 98 and 100, that one of the arms which is not subjected to the action of the cam meantime abuts against a concentric portion 45 of the cam, and that a portion of the movement of the lever 86 is effected by movement imparted to the arm 98 substantially in the direction of the length of the lever. The construction thus contributes to economy of 50 space and permits a cam of much smaller throw to be used than would be required if the cam were to act directly upon the lever 86. At the same time the mechanical advantage of a lever of comparatively long 55 throw, comprising substantially the sum of the lengths of the arms 86 and 100, is afforded at the time when the greatest resistance is encountered.

Operative movement is imparted to the driving shaft 90 from a belt pulley 116 through a suitable clutch, such as a Horton clutch, of which the controlling member is seen at 118 (Fig. 1), the member 118 being held normally in clutch releasing position by means of a stop pin 120 which is

yieldably mounted in one arm of a lever 122 pivoted on the base at 124. The lever 122 carries also a catch 126 for engagement with teeth on the clutch sleeve 128 to prevent back lash when movement of the member 70 118 is stopped by the pin 120. The lever 122 is operated to trip the clutch by means of a suitable treadle, not shown in the drawings, connected to a treadle rod 130 which operates a clutch tripping pin 132 to 75 impart movement through a latch 134 to the lever 122. It will be understood that when the clutch is tripped by the operation of the treadle the power shaft 90 is turned through one complete revolution to produce the operative movements hereinbefore described and then comes automatically to rest. In order to enable the operator to turn the machine over by hand when he so desires, a hand wheel 136 is provided on the outer 80 end of the shaft 90.

In the use of the machine, with the various parts of the mechanism in their idle positions as indicated in Figs 1, 2 and 3, the operator first positions a button piece such, 90 for example, as that part of the upper of a button shoe to which the buttons are attached, in the machine by inserting the number of buttons which it is desired to button downward into the auxiliary guiding forks 95 52 and into such position that the sides of the buttons are supported upon the upper ends of the rods 40 and the shanks are embraced by the forks 44. The auxiliary forks assist in guiding the buttons into the forks 100 44, and pressure of the buttons on one side or the other of the auxiliary forks also serves to effect any necessary adjustment of the several sets of instrumentalities through movement of the frames 14 as determined by the controlling member 32. The buttons having been thus positioned, the operator next positions the buttonhole fly as indicated in Fig. 3 with the fingers 105 54 extending through the button holes to 110 position them over the respective buttons and with the buttonhole fly resting upon the upper ends of the guiding forks 52. After the work has been thus positioned, the operator depresses the starting treadle. In 115 the first portion of the operative movement of the bar 80 the buttonhole fly engaging members 60 and 64 are moved downward toward the work, and as the movement of these members is continued the brackets 120 46 are also moved downwardly on the rods 40 to carry the buttonhole fly bodily toward the buttons and finally to withdraw the fingers 54 from the buttonholes and the forks 52 from engagement with the work. As 125 soon as the buttonhole fly encounters the resistance of the buttons, the fingers 62 on the arms 60 begin to force the material at the opposite sides of the buttonholes downward over the heads of the buttons, the spring 130

arms 64 in the meantime pressing against the buttonhole fly opposite to the inner ends of the alternate buttonholes and thus assisting during their sliding engagement with the work to carry the material down over the button heads as well as to prevent the material from being displaced by the action of the arms 60. In this manner the buttonhole fly is finally carried to the position indicated in Fig. 7 where the material at the opposite sides of the buttonhole has been forced substantially over the head of the button beyond the widest part of the head, with the fork 44 projecting through the buttonhole. By continued movement of the operating mechanism the parts are then returned to starting position, the work being discharged from the machine by the pressure either of the auxiliary forks 52 or of the fingers 54, or of both the forks and the fingers, against it during the upward movement of the brackets 46.

Having described the invention, what I claim as new and desire to secure by Letters Patent of the United States is:

1. A buttoning machine having, in combination, means for relatively positioning a button and a buttonhole fly with the button in edgewise relation to a buttonhole in said fly when the work is initially presented to the machine, and means for engaging the buttonhole fly and forcing it over the head of the button.

2. A buttoning machine having, in combination, means for relatively positioning a button and a buttonhole fly with the plane of the material about a buttonhole substantially perpendicular to the plane of the head of the button, and means for engaging the buttonhole fly and forcing it over the head of the button to cause the button to enter said buttonhole.

3. A buttoning machine having, in combination, means for relatively positioning a button and a buttonhole fly with the button in edgewise relation to an intermediate portion of a buttonhole in said fly, and buttonhole fly engaging means movable in a direction substantially parallel to the plane of the head of the button to perform a buttoning operation with respect to said button and buttonhole.

4. A buttoning machine having, in combination, means for relatively positioning a button and a buttonhole fly with the plane of the material about a buttonhole substantially perpendicular to the plane of the head of the button, a buttonhole fly engaging member, and means for moving said member laterally of the head of the button to perform a buttoning operation with respect to said button and buttonhole.

5. A buttoning machine having, in combination, means for relatively positioning a button and a buttonhole fly with the button

in edgewise relation to a buttonhole in said fly, a buttonhole fly engaging member having diverging portions constructed to extend down over the opposite sides of the head of the button in engagement with the material at the opposite sides of the buttonhole, and means for moving said member laterally of the head of the button to force the material laterally of the button axis over the button head.

6. A buttoning machine having, in combination, means for relatively positioning a button and a buttonhole fly with a buttonhole substantially opposite to the edge of the head of the button at one side of the button, and means for engaging the buttonhole fly at opposite sides of the buttonhole and forcing the material about the buttonhole against said adjacent side edge of the button head and then progressively over the button head into position for the material at the edges of the buttonhole to close inward substantially at the opposite side of the head.

7. A buttoning machine having, in combination, means for relatively positioning a button and a buttonhole fly with a buttonhole extending lengthwise in substantially perpendicular relation to the plane of the head of the button, and buttonhole fly engaging means constructed to engage said fly adjacent to the buttonhole and movable in a direction substantially parallel to the plane of the button head to force the material about the buttonhole over the button head.

8. A buttoning machine having, in combination, means for relatively positioning a button and a buttonhole fly with the button in edgewise relation to an intermediate portion of a buttonhole in said fly, and means for engaging the buttonhole fly at opposite sides of the buttonhole and forcing the material about the buttonhole over the head of the button.

9. A buttoning machine having, in combination, means for relatively positioning a button and a buttonhole fly with the plane of the side edge of the button head extending approximately perpendicular to the lengthwise dimension of a buttonhole, means constructed and arranged to engage the surface of the buttonhole fly at the end of the buttonhole and substantially along the opposite side edges of the buttonhole, and mechanism for effecting relative movement of said buttonhole fly engaging means and the button to perform a buttoning operation.

10. A buttoning machine having, in combination, means for relatively positioning a button and a buttonhole fly with a buttonhole extending lengthwise at an angle greater than 45° to the plane of the head of the button, and means for engaging the buttonhole fly at the end and the opposite sides of the buttonhole and forcing the material

about the buttonhole over the head of the button.

11. A buttoning machine having, in combination, means for relatively positioning a button and a buttonhole fly with a buttonhole extending lengthwise at an angle greater than 45° to the plane of the head of the button, a member arranged to engage the buttonhole fly at one end of the buttonhole and substantially at the opposite side edges of the buttonhole, and means for moving said member laterally of the head of the button to force the material about the buttonhole into buttoned relation to the button.

12. A buttoning machine having, in combination, means for relatively positioning a button and a buttonhole fly with a buttonhole extending lengthwise in transverse relation to the plane of the head of the button, and buttonhole fly engaging members arranged to engage the buttonhole fly substantially at opposite ends of the buttonhole and movable one over the top of the button head and the other substantially under the shank of the button to force the material adjacent to the buttonhole into buttoned relation to the button.

13. A buttoning machine having, in combination, means for relatively positioning a button and a buttonhole fly with a buttonhole extending lengthwise in transverse relation to the plane of the head of the button, a member arranged to engage the buttonhole fly substantially at one end of the buttonhole and to move laterally of the head of the button over the top of the head to force the material adjacent to the buttonhole into buttoned relation to the button, and another member constructed and arranged for yieldable sliding engagement with the material substantially at the opposite end of the buttonhole to assist in forcing the material over the button.

14. A buttoning machine having, in combination, means for relatively positioning a button and a buttonhole fly with a buttonhole extending lengthwise in transverse relation to the plane of the head of the button, and buttoning members arranged to engage the buttonhole fly substantially at opposite ends of the buttonhole, one of said members being constructed and arranged to apply yielding pressure to the buttonhole fly substantially under the shank of the button while the other member is forcing the material over the head of the button.

15. A buttoning machine having, in combination, means for relatively positioning a button and a buttonhole fly with a buttonhole extending lengthwise in transverse relation to the plane of the head of the button, buttoning members arranged to engage the buttonhole fly substantially at opposite ends of the buttonhole, and means for moving

said members laterally of the button to force the material adjacent to the buttonhole over the head of the button, one of said members being constructed of resilient material for yieldable sliding engagement with a portion of the buttonhole fly substantially under the shank of the button.

16. A buttoning machine having, in combination, means for relatively positioning a button and a buttonhole fly with a buttonhole extending lengthwise in transverse relation to the plane of the head of the button, a buttoning member constructed and arranged to engage the buttonhole fly substantially at one end of the buttonhole, operating means for moving said member laterally of the button over the top of the button head to force the material adjacent to the buttonhole over the head of the button, and an arm of resilient material carried by said operating means and arranged for yieldable sliding engagement with the material substantially at the opposite end of the buttonhole to assist in the buttoning operation.

17. In a buttoning machine, the combination with means for positioning a button, of buttonhole fly engaging members constructed and arranged to engage the material of the buttonhole fly substantially at the opposite ends of the buttonhole and to force the material over the head of the button, one of said members being constructed for yieldable sliding engagement with the work to resist the tendency of the other member to displace the work.

18. In a buttoning machine, the combination with means for positioning a button, of means for engaging the buttonhole fly at one end and the opposite sides of a buttonhole and forcing the material about the buttonhole over the head of the button, and means for engaging the buttonhole fly yieldingly substantially at the opposite end of the buttonhole to restrain it against displacement.

19. A buttoning machine having, in combination, means for relatively positioning a button and a buttonhole fly with the portion of the buttonhole fly about a buttonhole lying in a plane substantially perpendicular to the plane of the button head, and means for effecting relative movement of the button and the buttonhole fly to force the material about the buttonhole into buttoned position while the parts of the work are maintained substantially in said relation.

20. A buttoning machine having, in combination, means for relatively positioning a button and a buttonhole fly with a buttonhole extending lengthwise in transverse relation to the plane of the button head, and means for effecting relative movement of the buttonhole fly and the button to dispose the material about the buttonhole in buttoned relation to the button without substantially

altering said transverse relation between the buttonhole and the plane of the button head.

21. A buttoning machine having, in combination, means for relatively positioning 5 a button and a buttonhole fly with a button-hole extending lengthwise in substantially perpendicular relation to the plane of the head of the button, and means for engaging the buttonhole fly substantially at opposite 10 sides of the buttonhole and moving that portion of the buttonhole fly which lies about the buttonhole bodily over the head of the button while maintaining the parts of the work substantially in said relation.
- 15 22. A buttoning machine having, in combination, means for positioning a button, and means for engaging a buttonhole fly at opposite sides of a buttonhole and forcing the material about the buttonhole over the 20 head of the button in a direction to cause the button to enter the buttonhole edgewise.

23. A buttoning machine having, in combination, means for positioning a button, and means for engaging a buttonhole fly and 25 forcing that portion of said fly which lies about a buttonhole bodily over the head of the button in a direction substantially parallel to the plane of the head.

24. A buttoning machine having, in combination, button positioning means arranged 30 to engage a button on one side of the button head, and means for engaging a buttonhole fly at the opposite side of the button and forcing it over the head of the button while the button is thus positioned.

25. A buttoning machine having, in combination, means for positioning a button, means for positioning a buttonhole fly with 40 an intermediate portion of a buttonhole substantially opposite to the edge of the head of the button at one side of the button, and buttonhole fly engaging means mounted for swinging movement laterally of the buttonhead to force the material about the buttonhole laterally over the head.

26. A buttoning machine having, in combination, button positioning means comprising a member for engaging a button on one side of the button head, and buttonhole fly 50 engaging means movable laterally of the button toward said member from the opposite side of the button to force the buttonhole fly over the head of the button.

27. A buttoning machine having, in combination, button positioning means provided with a slot to receive the shank of a button, means for positioning a buttonhole fly with the portion of the fly adjacent to a button-hole extending transversely across the end 60 of said slot, and means for forcing the buttonhole fly over the head of the button while the shank of the button remains in said slot.

28. A buttoning machine having, in combination, button positioning means provided 65 with a slot to receive the shank of a button,

means for positioning a buttonhole fly transversely across the end of said slot with a buttonhole extending lengthwise in substantially perpendicular relation to the plane of the head of the button, and means for engaging the buttonhole fly substantially at opposite sides of the buttonhole and forcing the material about the buttonhole over the head of the button while the shank of the button remains in said slot.

75

29. A buttoning machine having, in combination, button positioning means provided with a slot to receive the shank of a button and with means for engaging one side of the head of the button to support the button, 80 means for engaging a buttonhole fly substantially at the opposite side of the head of the button, and mechanism for operating said buttonhole fly engaging means to perform a buttoning operation while the button 85 is thus positioned.

30. A buttoning machine having, in combination, button positioning means comprising a fork to receive the shank of a button, said fork being so constructed as to permit 90 it to enter a buttonhole, buttonhole fly engaging means, and mechanism for effecting relative movement of said button positioning means and buttonhole fly engaging means to cause said fork to enter a button- 95 hole approximately at right angles to the plane of the material about the buttonhole and to cause the material about the buttonhole to be forced over the head of the button.

100

31. A buttoning machine having, in combination, button positioning means comprising a fork to receive the shank of a button and a member for engaging one side of the button head to support the button, said fork 105 being so constructed as to permit it to enter a buttonhole, means for engaging a button-hole fly substantially at the opposite side of the button, and mechanism for effecting relative movement of said button positioning means and buttonhole fly engaging means to cause said fork to enter a button- 110 hole and the material about the buttonhole to be forced over the head of the button.

32. A buttoning machine having, in combination, button positioning means comprising a fork to receive the shank of a button, said fork being so constructed as to permit it to enter a buttonhole, means for positioning a buttonhole fly transversely across the 115 end of said fork, and means for engaging said buttonhole fly and moving that portion of the fly which lies about a buttonhole laterally of the button to cause said fork to enter the buttonhole and the material about 120 the buttonhole to be forced over the head of the button.

33. A buttoning machine having, in combination, button positioning means comprising a fork to receive the shank of a button, 130

5 said fork being so constructed as to permit it to enter a buttonhole, means for positioning a buttonhole fly transversely of said fork with a buttonhole extending lengthwise in transverse relation to the plane of the head of the button, and means for engaging the buttonhole fly substantially at the opposite sides of the buttonhole and moving that portion of the fly which lies about the buttonhole laterally of the button to cause said fork to enter the buttonhole and the material about the buttonhole to be forced over the head of the button.

34. A buttoning machine having, in combination, button positioning means comprising a fork to receive the shank of a button, said fork being so constructed as to permit it to enter a buttonhole, buttonhole fly engaging means constructed to engage the fly substantially at the opposite side edges of a buttonhole, and mechanism for effecting relative movement of said button positioning means and buttonhole fly engaging means in a direction substantially lengthwise of said fork to cause the fork to enter the buttonhole and the material lying about the buttonhole to be forced over the head of the button.

35. A buttoning machine having, in combination, button positioning means comprising a fork to receive the shank of a button, and means for engaging a buttonhole fly adjacent to a buttonhole and moving the material that lies about the buttonhole lengthwise of said fork to force it over the head of the button while the shank of the button remains in the fork.

36. A buttoning machine having, in combination, a button positioning fork, means for positioning a buttonhole fly with the material about a buttonhole extending transversely of the lengthwise dimension of said fork, and means for engaging the buttonhole fly and forcing it over the head of the button in a direction to cause the button to enter the buttonhole edgewise.

37. A buttoning machine having, in combination, an upwardly directed button positioning fork, and buttonhole fly engaging means mounted to swing downwardly along said fork and to force the material about a buttonhole over a button in said fork to cause the button to enter the buttonhole edgewise.

38. A buttoning machine having, in combination, a button positioning fork adapted to enter a buttonhole of a buttonhole fly, and buttonhole fly engaging members mounted for movement lengthwise of said fork in engagement respectively with portions of the fly at opposite sides of a buttonhole to cause the buttonhole to pass around the fork in buttoned relation to a button in the fork.

39. A buttoning machine having, in combination, a button positioning fork, and but-

tonhole fly engaging members mounted for movement lengthwise of said fork and respectively over the top of the button head and under the shank of the button in the fork to dispose the material about a buttonhole in buttoned relation to the button.

40. A buttoning machine having, in combination, means for positioning a button, a member arranged to extend laterally of the button for engagement in a buttonhole to position the buttonhole opposite to one side of the button, and buttonhole fly engaging means movable laterally of the button to perform a buttoning operation with respect to said button and buttonhole.

41. A buttoning machine having, in combination, a button receiving fork, a member arranged to extend laterally of the button for engagement in a buttonhole to position the buttonhole fly substantially across the end of said fork, and buttonhole fly engaging means movable lengthwise of the fork, to force the material about the buttonhole over the head of the button.

42. A buttoning machine having, in combination, means for positioning a button, a member arranged to extend laterally of the button for engagement in a buttonhole to position the buttonhole opposite to one side of the button, means for performing a buttoning operation with respect to the button and the buttonhole, and means for withdrawing said member from the buttonhole to permit the buttoning operation to be performed.

43. A buttoning machine having, in combination, means for positioning a button, buttonhole fly positioning means comprising a member arranged to extend laterally of the button for engagement in a buttonhole to position the buttonhole substantially opposite to one side of the button, buttonhole fly engaging means, mechanism for effecting relative movement of said button positioning means and buttonhole fly engaging means to perform a buttoning operation, and mechanism for withdrawing said member from the buttonhole to permit the buttoning operation to be performed.

44. A buttoning machine having, in combination, means for positioning a button, buttonhole fly positioning means comprising a member arranged to extend laterally of the button for engagement in a buttonhole to position the buttonhole substantially opposite to one side of the button, means for engaging the buttonhole fly and forcing it over the head of the button, and means for withdrawing said member from the buttonhole to permit the buttoning operation to be performed.

45. A buttoning machine having, in combination, means for positioning a button, a member arranged to extend in substantially parallel relation to the plane of the button

head for engagement in a buttonhole to position the buttonhole in transverse relation to the plane of the button head, means for engaging the buttonhole fly and forcing it over the head of the button, and means for withdrawing said member from the buttonhole to permit the buttoning operation to be performed.

46. A buttoning machine having, in combination, means for positioning a button, a member arranged to extend laterally of the button for engagement in a buttonhole to position the buttonhole relatively to the button, buttonhole fly engaging means movable laterally of the button to force the material about the buttonhole over the head of the button, and means for moving said member in substantially the same direction as said buttonhole fly engaging means to withdraw the member from the buttonhole.

47. A buttoning machine having, in combination, a button positioning fork arranged to receive the shank of a button, a member projecting in substantially parallel relation to said fork for engagement in a buttonhole to position the buttonhole relatively to the button, means for performing a buttoning operation with respect to the button and the buttonhole, and means for moving said member lengthwise of the fork to withdraw it from the buttonhole.

48. In a buttoning machine, the combination with button positioning means, of a member arranged to extend laterally of the button for engagement in a buttonhole to position the buttonhole fly in transverse relation to the plane of the button head, said member and the button positioning means being relatively movable in a direction lengthwise of the member to cause the member to be withdrawn from the buttonhole.

49. A buttoning machine having, in combination, means for positioning a button, a member arranged to extend laterally of the button for engagement in a buttonhole to position the buttonhole fly in transverse relation to the plane of the button head, buttonhole fly engaging means, and mechanism for moving said buttonhole fly engaging means to force the material about the buttonhole over the head of the button and for simultaneously moving said member in a direction to withdraw it from the buttonhole.

50. In a buttoning machine, a bar having an end portion constructed to position a button for a buttoning operation, and buttonhole fly positioning means comprising a member arranged to engage in a buttonhole to position the buttonhole relatively to the button, said buttonhole fly positioning means being mounted for movement along said bar into and out of operative position.

51. A buttoning machine having, in combination, a bar provided with a forked end portion to receive the shank of a button, but-

tonhole fly positioning means mounted for sliding movement along said bar and comprising a member arranged to project laterally of the button for engagement in a buttonhole, means for engaging the buttonhole fly and forcing it over the head of the button, and mechanism connected to said buttonhole fly engaging means for moving the buttonhole fly positioning means along said bar to withdraw said member from the buttonhole.

52. A buttoning machine having, in combination, means for positioning a button, buttonhole fly positioning means comprising a member arranged to extend laterally of the button for engagement in a buttonhole, buttonhole fly engaging means movable to force the material about the buttonhole over the head of the button, and connections between said buttonhole fly engaging means and buttonhole fly positioning means for withdrawing said member from the buttonhole, said connections including provision for lost motion to permit the buttonhole fly engaging means to be located initially in a position in which it presents no obstruction to the presentation of the work to the machine.

53. A buttoning machine having, in combination, button positioning means arranged to receive a button when the work is initially presented to the machine, means for guiding the button to said button positioning means, buttoning means for performing a buttoning operation with respect to the button, and mechanism for effecting relative movement of said button positioning means and button guiding means during the operation of the buttoning means to cause the guiding means to be disposed in inoperative relation to the button positioning means.

54. A buttoning machine having, in combination, button positioning means arranged to receive a button when the work is initially presented to the machine, means for guiding the button to said button positioning means, buttoning means for performing a buttoning operation with respect to the button, and power-operated mechanism acting in timed relation to the operation of the buttoning means to cause said guiding means to be withdrawn to an inoperative position.

55. A buttoning machine having, in combination, button positioning means, means for guiding a button to said button positioning means, means for engaging a buttonhole fly and forcing it over the head of the button in said positioning means, and mechanism for moving said button guiding means during the operative movement of said buttonhole fly engaging means to withdraw the guiding means to an inoperative position.

56. A buttoning machine having, in combination, button positioning means, means for guiding a button to said button positioning means, means for positioning a buttonhole fly in transverse relation to the plane of

the head of the button, means for engaging the buttonhole fly and forcing it over the head of the button, and means for withdrawing said button guiding means to an inoperative position to permit the buttonhole fly to be forced over the head of the button.

57. A buttoning machine having, in combination, button positioning means, means for guiding a button to said button positioning means, buttonhole fly engaging means, mechanism for operating said buttonhole fly engaging means to force the material about a buttonhole over the head of the button, and connections between said mechanism and said guiding means for withdrawing the guiding means to an inoperative position.

58. In a buttoning machine, the combination with button positioning means provided with a slot to receive the shank of a button, of means for guiding the button into said slot, said button positioning means and button guiding means being relatively movable lengthwise of said slot to cause the guiding means to be disposed in inoperative relation to the button positioning means.

59. In a buttoning machine, the combination with button positioning means provided with a slot to receive the shank of a button, of button guiding means having a button receiving opening arranged to direct the button into said slot, said guiding means being movable lengthwise of said slot into and out of operative position.

60. In a buttoning machine, a button receiving fork, and a button guiding device constructed to form substantially an extension of said fork and movable lengthwise of the fork into and out of operative position.

61. A buttoning machine having, in combination, a button positioning fork, means for guiding a button into said fork, buttonhole fly engaging means movable lengthwise of said fork to force the material about a buttonhole over the head of the button, and mechanism for withdrawing said guiding means from operative position to permit the buttoning operation to be performed.

62. A buttoning machine having, in combination, button positioning means, a fork arranged to direct a button to said button positioning means, means for positioning a buttonhole fly across the end of said fork, and means for engaging the buttonhole fly and forcing it over the head of the button and for simultaneously withdrawing said fork to an inoperative position.

63. In a buttoning machine, button positioning means comprising a bar having an end portion constructed to provide a fork to embrace the shank of a button, and a device for guiding the button into said fork, said device being mounted for sliding movement along said bar into and out of operative position.

64. In a buttoning machine, the combina-

tion with button positioning means, of a guide arranged to direct a button to said button positioning means, and a member arranged to project through a buttonhole to position the buttonhole fly relatively to the button, said guide and member being movable together into and out of operative position.

65. In a buttoning machine, the combination with button positioning means, of an upwardly directed fork arranged to guide a button to said button positioning means, a member at the rear of said fork arranged to project beyond the end of the fork for engagement in a buttonhole to position the buttonhole fly relatively to the button, means for engaging the buttonhole fly and forcing it over the head of the button, and means for moving said fork and member together to withdraw them from operative position.

66. In a buttoning machine, the combination with button positioning means, of a fork arranged to guide a button to said button positioning means, means connected to said fork for positioning a buttonhole fly across the end of the fork, means for engaging the buttonhole fly and forcing it over the head of the button, and mechanism movable in timed relation to said buttonhole fly engaging means for withdrawing said fork and buttonhole fly positioning means from operative position.

67. In a buttoning machine, the combination with a button positioning fork, of a button guiding device constructed to form substantially an extension of said fork, and a member extending lengthwise of the fork and arranged to project through a buttonhole to position the buttonhole fly relatively to the button, said member and guiding device being movable together lengthwise of the fork into and out of operative position.

68. In a buttoning machine, the combination with a bar having an end portion constructed to provide a fork to receive the shank of a button, of a device movable along said bar into and out of operative position and having different portions constructed respectively for guiding a button into said fork and for positioning the buttonhole fly relatively to the button in the fork.

69. In a buttoning machine, the combination with means for performing a buttoning operation with respect to a button and a buttonhole fly, of means for guiding the button into the machine when the work is presented, and means for causing the work to be ejected from the machine by the action of said guiding means after the buttoning operation has been performed.

70. A buttoning machine having, in combination, means for positioning a button for a buttoning operation, means for guiding the button to said button positioning means,

- and means for performing a buttoning operation with respect to the button and for operating said guiding means to eject the work from the machine.
- 5 71. A buttoning machine having, in combination, button positioning means, means for guiding a button to said button positioning means, means for performing a buttoning operation with respect to the button, and 10 means for withdrawing said button guiding means to an inoperative position and for subsequently operating said guiding means to eject the work from the machine.
- 15 72. In a buttoning machine, the combination with button positioning means, of means for guiding a button to said button positioning means, said button guiding means and button positioning means being relatively movable first to permit a buttoning operation to be performed upon the button in the positioning means and subsequently to cause the work to be ejected from the machine by the action of the guiding means.
- 20 73. In a buttoning machine, the combination with a button positioning fork, of means for guiding a button into said fork, means for performing a buttoning operation with respect to the button in the fork, and means 25 for withdrawing said guiding means to an inoperative position to permit the buttoning operation to be performed and for subsequently returning the guiding means to operative position, said guiding means being so constructed and arranged as to 30 eject the button from the fork during its return to operative position.
- 35 74. In a buttoning machine, the combination with a button positioning fork, of a button guiding device constructed to form substantially an extension of said fork when the parts of the machine are in their initial positions, and means for moving said guiding device lengthwise of the fork to withdraw it from operative position and for subsequently returning it to its initial position to cause it to eject the button from the fork.
- 40 75. In a buttoning machine, the combination with means for performing a buttoning operation with respect to a button and a buttonhole fly, of means for positioning the buttonhole fly when the work is initially presented to the machine, and means for causing the work to be ejected from the machine by 45 the action of said buttonhole fly positioning means after the buttoning operation has been performed.
- 50 76. In a buttoning machine, the combination with means for performing a buttoning operation with respect to a button and a buttonhole fly, of buttonhole fly positioning means, and means for withdrawing said buttonhole fly positioning means to an inoperative position to permit the buttoning 55 operation to be performed and for subsequently operating said positioning means to 60 eject the work from the machine.
- 65 77. In a buttoning machine, the combination with buttoning means, of a member arranged to project through a buttonhole to 70 position the buttonhole fly for the buttoning operation, and means for withdrawing said member from the buttonhole to permit the buttoning operation to be performed and for subsequently returning the member to starting position, said member being so constructed and arranged as to eject the work from the machine during its return to starting position.
- 75 78. In a buttoning machine, the combination with means for positioning a button, of a member arranged to project laterally of the button for engagement in a buttonhole to position the buttonhole fly opposite to one side of the button, means for engaging the buttonhole fly and forcing it over the head of the button, and means for withdrawing said member from the buttonhole to permit the buttoning operation to be performed and for subsequently operating said member to 80 eject the work from the machine.
- 85 79. In a buttoning machine, the combination with a button positioning fork, of a member arranged to project lengthwise of said fork for engagement in a buttonhole, 90 said fork and member being relatively movable first to cause the member to be withdrawn from the buttonhole and then to cause the member to engage the work and eject it from the machine.
- 95 80. A buttoning machine having, in combination, means for relatively positioning a plurality of buttons and a buttonhole fly with the buttons in edgewise relation to the buttonholes when the work is initially presented to the machine, and means for engaging the material adjacent to a plurality of buttonholes and forcing it over the heads of the corresponding buttons while the parts of the work are maintained substantially in 100 said relation.
- 105 81. A buttoning machine having, in combination, means for positioning a row of buttons on a button piece with side edges of the heads of the buttons directed upward, and means for engaging a buttonhole fly and forcing it down substantially simultaneously over the several buttons in a direction substantially parallel to the planes of the heads of the buttons to cause the buttons to enter 110 the buttonholes edgewise.
- 115 82. A buttoning machine having, in combination, a plurality of button positioning forks and means for effecting relative movement of said forks and a buttonhole fly to 120 cause the forks to pass endwise into the several buttonholes of the fly substantially simultaneously and to cause the material

about the buttonholes to be forced over the heads of the buttons while the buttons remain in the forks.

83. A buttoning machine having, in combination, a plurality of upwardly directed button positioning forks constructed and arranged to permit them to enter the buttonholes of a buttonhole fly, means for positioning a buttonhole fly in transverse relation to the lengthwise dimensions of said forks, and means for engaging the buttonhole fly and forcing it down over the ends of the several forks substantially simultaneously to dispose the material about the buttonholes in buttoned relation to the buttons.

84. A buttoning machine having, in combination, means for relatively positioning a plurality of buttons and a buttonhole fly with the buttons presented edgewise in transverse relation to the lengthwise dimensions of the buttonholes, a plurality of buttonhole fly engaging members constructed to engage the material about the several buttonholes, and means for operating said members substantially simultaneously to move the material about the buttonholes progressively over the heads of the buttons from edge to edge thereof.

85. A buttoning machine having, in combination, means operable on a buttonhole fly to perform a buttoning operation with respect to a buttonhole of the fly and a button, and a stationary fork for supporting the button by engagement with the head of the button during the performance of the entire buttoning operation.

86. A buttoning machine having, in combination, means movable substantially at right angles to the portion of a buttonhole fly about a buttonhole for performing a buttoning operation with respect to said buttonhole and a button, and a stationary fork for supporting the button by engagement with the head of the button during the performance of the entire buttoning operation.

87. A buttoning machine having, in combination, means for supporting a button by engagement with the side of the head of the button and means operable on a buttonhole

fly to perform a buttoning operation with respect to a buttonhole of the fly and said button.

88. A buttoning machine having, in combination, a fork to receive the shank of a button and means stationary with respect to said fork for supporting the button by engagement with the side of the head of the button.

89. A buttoning machine having, in combination, means for relatively positioning a button on a button piece and a buttonhole fly with the button in edgewise relation to an intermediate portion of a buttonhole in the fly and means for performing a buttoning

operation with respect to said button and buttonhole comprising means for moving the material of the buttonhole fly on both sides of the buttonhole simultaneously toward the button piece.

90. A buttoning machine having, in combination, means for relatively positioning the buttons of a button piece and a buttonhole fly with the plane of the axes of the buttons approximately parallel to the plane of the buttonholes, and buttonhole fly engaging means movable in a direction substantially at right angles to the plane of the axes of the buttons to perform a buttoning operation with respect to said buttons and buttonholes.

91. A buttoning machine having, in combination, means for relatively positioning a button and a buttonhole fly with the axis of the button approximately parallel to the plane of the material adjacent to a buttonhole in said fly, and buttonhole fly engaging means movable in a direction substantially parallel to the plane of the head of the button to perform a buttoning operation with respect to said button and buttonhole.

92. A buttoning machine having, in combination, means for relatively positioning a button and a buttonhole fly with the axis of the button approximately parallel to the plane of the material adjacent to a buttonhole in said fly, a buttonhole fly engaging member having diverging portions constructed to extend down over the opposite sides of the head of the button in engagement with the material at the opposite sides of the buttonhole, and means for causing relative movement of said member and the head of the button laterally of the latter to perform the buttoning operation.

93. A buttoning machine having, in combination, means for relatively positioning a button and a buttonhole fly with the axis of the button approximately parallel to the plane of the buttonholes in said fly, and means for engaging the buttonhole fly simultaneously at the end and the opposite sides of the buttonhole to sustain the material about the buttonhole during the buttoning operation.

94. A buttoning machine having, in combination, means for positioning a button and a buttonhole fly with the axis of the button approximately parallel to the plane of the material adjacent to a buttonhole in said fly and a forked member for causing relative movement of the button and that portion of said fly which lies about the buttonhole in a direction substantially at right angles to the axis of the button to perform the buttoning operation.

95. A buttoning machine having, in combination, means for positioning a button, and means for engaging a buttonhole fly at opposite sides of a buttonhole and relatively

moving the button and the material about the buttonhole in a direction approximately at right angles to the axis of the button to perform the buttoning operation.

5 96. A buttoning machine having, in combination, button positioning means arranged to engage a button on one side of the button head, a buttonhole fly engaging means, and means for effecting relative movement of 10 said button positioning means and said fly engaging means to perform a buttoning operation.

97. A buttoning machine having, in combination, buttoning instrumentalities comprising means operable to hold the work against displacement and means to pass a button through a buttonhole while so held and power driven mechanism comprising a rotatable cam and mechanism for rendering 20 the same portion of said cam repeatedly effective during a single rotation of the cam to operate first said holding means and thereafter said means for passing the button through the buttonhole.

25 98. A buttoning machine having, in combination, buttoning instrumentalities comprising means for passing a button through a buttonhole and means for preventing displacement of the work as the button is passed 30 through the buttonhole, and mechanism for operating said buttoning instrumentalities comprising a rotatable cam and a lever serving to transmit power from said cam to said buttoning instrumentalities and fulcrumed 35 between its ends, said lever being constructed and arranged to cause its opposite end portions to be operated upon by the same portion of the cam successively while the other end portions of said lever abut against the 40 cam to operate in turn the displacement preventing means and the means for passing the button through the buttonhole.

45 99. In a buttoning machine, the combination of means for relatively positioning a button and a buttonhole adjacent to one another, buttoning instrumentalities comprising means to pass the button through the buttonhole and means to prevent displacement of the work while the button is passed 50 through the buttonhole, and means for operating said buttoning instrumentalities comprising a power transmitting member, a rotatable cam provided with concentric portions and a lever carried by said member 55 for transmitting movement from the cam to

the member, said lever being constructed and arranged to cause one of its end portions to be operated by the cam while its other end portion fulcrums on a concentric portion of the cam to render operative said displacement preventing means and thereafter to cause said other end portion to be operated by the cam while the first end portion abuts against a concentric portion of the cam to operate the means for passing the button through the buttonhole.

100. A buttoning machine having, in combination, buttoning instrumentalities comprising means for passing a button through a buttonhole and means to prevent displacement of the work while the button is passed through the buttonhole, and means for transmitting power to operate said buttoning instrumentalities comprising a rotatable cam, a pivoted lever having an arm extending 75 toward the cam and of less length than the distance between the axis of the lever and the cam and a bell-crank lever pivotally mounted at the outer end of said arm and arranged to cause the same portion of the 80 cam to operate successively on different respective arms of the bell crank lever to transmit substantially continuous movement to the first-named lever in one direction during a single rotation of the cam, the operation of the cam upon the first arm of the bell-crank lever serving to transmit power to the buttoning instrumentalities to operate the displacement prevention means, and the transmission of power from the cam to 85 the second arm of the bell-crank lever serving to transmit power to the buttoning instrumentalities to pass the button through the buttonhole.

101. A buttoning machine having, in combination, buttoning instrumentalities and mechanism for operating said buttoning instrumentalities comprising a rotatable cam and a lever serving to transmit power from said cam to said buttoning instrumentalities 100 and fulcrumed between its ends, said lever being constructed and arranged to cause its opposite end portions to be operated upon by the same portion of the cam successively while the other respective end portions of 105 said lever abut against the cam.

In testimony whereof I have signed my name to this specification.

LEWIS J. BAZZONI.
